No. 703,864.

Patented July 1, 1902.

W. R. WALKER.

NAPKIN SUPPORT.

(Application filed Mar. 25, 1902.)

(No Model.)

UNITED STATES PATENT OFFICE.

WILLIAM R. WALKER, OF SABULA, IOWA.

NAPKIN-SUPPORT.

SPECIFICATION forming part of Letters Patent No. 703,864, dated July 1, 1902.

Application filed March 25, 1902. Serial No. 99,927. (No model.)

To all whom it may concern:

Be it known that I, WILLIAM R. WALKER, a citizen of the United States, residing at Sabula, in the county of Jackson and State of Iowa, 5 have invented certain new and useful Improvements in Napkin-Supports; and I do declare the following to be a full, clear, and exact description of the invention, such as will enable others skilled in the art to which it applies to make and use the same.

This invention relates to a device for supporting napkins upon the person; and its object is to provide a simple, cheap, and convenient construction of device which may be 15 readily applied and removed and which will effectually support the napkin in position.

The invention consists of certain novel features and parts and combinations of the same, as will be fully described hereinafter and then 20 pointed out in the claim.

A practical embodiment of the invention is represented in the accompanying drawings, in which similar characters of reference indicate corresponding parts in all the views.

25 Figure 1 is a perspective view showing the manner in which a napkin is attached to the support. Fig. 2 is a plan view of the support, showing the clasp closed; and Fig. 3 is a longitudinal section showing the clasp open.

30 The holder comprises a split spring-metal band or ring 1, which is adapted to be opened to admit of its application about the neck of the wearer and to close by its own resiliency, so as to encompass the neck of the person and 35 be held in position. This band is composed of two sections 2 and 3, united by a rivet 4. The inner end of the section 2 is connected to the intermediate portion of the section 3 by the rivet 4, while the inner end of the latter section laps over upon the outer surface

40 of said section 2 and forms a spring-clasp 5. The free end of this clasp carries a stud 6, having a shank 7, which is slidably fitted in a longitudinal slot 8 in the section 2 and is 45 held against displacement by a washer 9; bear-

ing against the inner face of said section, said washer being held by riveting or upsetting the end of the shank. By this construction it will be seen that upon sliding the stud in one direction, as shown in Fig. 3, the clasp 7 50 will be bowed or forced out, so that one of the corners of the napkin may be inserted between the same and the band, while upon sliding the stud in the other direction the clasp will be allowed to close by its natural 55 resiliency and clamp the napkin against the band.

In order to adjust the napkin upon the person, one of the corners of the napkin is clamped as described and as shown in Fig. 1, 60 and then the band is placed about the neck of the wearer, allowing the napkin to hang down in proper position. To remove the napkin from the person, it is simply necessary to unclasp the band from the neck, as will be 65 readily understood. The manner of attaching the napkin to and detaching it from the band has been previously described, and it will be seen that a simple and effective device for the purpose stated is provided. 70

Having thus described my invention, what I claim, and desire to secure by Letters Patent, is—

A napkin holder and support consisting of a spring-band formed of two sections, one of 75 said sections having an intermediate slot and connected at one end to the intermediate portion of the other section, the latter having an end overlapping the first-named section and forming a spring-clasp, and a stud carried by 80 the free end of said clasp and sliding in said slot, substantially as set forth.

In testimony whereof I have hereunto set my hand in presence of two subscribing witnesses.

WM. R. WALKER.

Witnesses:

W. T. BERNER,
F. H. WULFF.
